UNITED STATES PATENT OFFICE

2,531,949

FUSE TUBE TERMINAL

Carl E. Schultheiss, Libertyville, Ill., assignor to
 S & C Electric Company, Chicago, Ill., a corporation of Delaware

Application March 22, 1948, Serial No. 16,179

4 Claims. (Cl. 173—269)

1

This invention relates, generally, to terminals and it has particular relation to terminals for expulsion fuse tubes.

In the fuse constructions shown in Ramsey Patents Nos. 2,108,993 and 2,247,700 and in McMahon Patent No. 2,253,720 fuse links are employed which have rigid anchor contact members or cone terminals that interfit with correspondingly shaped sockets in the terminals at the discharge ends of the fuse tubes. Spring tension is applied to the fuse links in these constructions so that the cone terminals are held in the cone shaped sockets under spring tension to provide low resistance electrical contact with the terminals. In these bayonet type fuse devices or cut outs the diameter of the housing and the contacts carried thereby as well as the diameter of the fuse tube and its bayonet contacts must be kept at minimum values to make the device economical to manufacture.

It is sometimes the case that it is desirable in the field to employ fuse links for these fuse constructions which are not provided with the rigid anchor contact members or cone terminals and which are furnished by different manufacturers. Also it may be desirable to employ fuse links with or without cone terminals in the fuse tubes in these constructions without employing the spring and cable assembly which is shown as being provided to maintain the fuse link under tension and to withdraw the sleeve of the link within the fuse tube when the link blows.

In Ramsey Patent No. 2,247,700 the lower fuse tube terminal is provided with a clamp member held by a set screw for clamping the flexible conductor of the fuse link to the terminal. However, such a construction is not feasible for the bayonet type of fuse mechanism shown in Ramsey Patent No. 2,108,993 and McMahon Patent No. 2,253,720 because of space limitations, interference with venting resulting in lowering of the interrupting capacity of the cut out and other practical difficulties.

Accordingly, among the objects of this invention are: To provide a terminal construction for the discharge end of an expulsion type fuse tube for accommodating fuse links having rigid anchor contact members or cone terminals on the flexible leads and to accommodate fuse links without the rigid anchor contact members or cone terminals on the flexible leads; to employ a single terminal construction for accommodating either type of fuse link and for making connection either to the cone terminal or to the flexible lead as the case may be; to arrange the clamp con-

2

struction so that it does not interfere with the insertion of the fuse tube in the fuse housing for a bayonet type of fuse device; to construct the clamp mechanism so that it will not interfere with the discharge of the products of the arc resulting from the blowing of the fuse link and will not be damaged by the heat of the arc; to accommodate different makes of fuse links; to provide a construction the removable clamp portion of which is a standard article of commerce that is usually carried on all linemen's trucks rather than a special clamp mechanism which if lost when separated from the remainder of the terminal construction could not be replaced readily; and to provide a solution to the problem of accommodating various types of fuse links in a given fuse tube and terminal design of such dimensions as to permit its interchangeable use within the confines of the insulating housing, such as shown in Patent No. 2,108,993, having no exposed live parts, which has been applied extensively on several electric power systems throughout this country.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention reference can be had to the following detailed description, taken together with the accompanying drawings, in which:

Figure 1 is a view, in side elevation, of a bayonet type fuse device, such as that shown in Ramsey Patent No. 2,108,993 or McMahon Patent No. 2,253,720, in which the present invention is incorporated;

Figure 2 is a longitudinal sectional view of the fuse tube which is arranged to be connected to a handle and inserted in the fuse housing shown in Figure 1, the terminal at the discharge end of the fuse tube being constructed in accordance with this invention and having the flexible lead of the fuse link clamped thereto;

Figure 3 is a detailed sectional view at an enlarged scale, taken along the line 3—3 of Figure 2 and showing a part of the lower portion of the housing shown in Figure 1;

Figure 4 is a view, similar to Figure 2, and

showing how a fuse link provided with a cone terminal can be employed in conjunction with a spring and cable assembly in lieu of the construction shown in Figure 2; and

Figure 5 is a view, similar to Figure 4, showing how the fuse link construction illustrated in McMahon Patent No. 2,253,720 can be employed in conjunction with the present invention where a spring and cable assembly is employed.

Referring now particularly to Figure 1 of the drawings, it will be observed that the reference character 10 designates, generally, a bayonet type cut out such as that shown and described in more detail in Ramsey Patent No. 2,108,993. The cut out 10 is arranged to be mounted on a cross arm 11 or like support. For this purpose a clamp 12 may be provided which supports the cut out 10 by means of a bracket 13. The cut out 10 includes a corrugated tubular body or housing 14 of insulating material such as porcelain.

The cut out 10 also includes a handle 15 of insulating material, such as porcelain, and it is arranged to be threaded onto a terminal 16 which is located at the upper end of a fuse tube 17. As shown in Figure 2 the fuse tube 17 is formed of insulating material. For example, it may have a liner of fiber and an outer covering of a phenolic condensation product. In Figure 2 of the drawings the parts are shown full size. However, it will be understood that this is for illustrative purposes only and that various sizes and dimensions can be employed depending upon the operating conditions.

Within the fuse tube 17 there may be located a fuse link which is indicated, generally, at 29. The fuse link 29 may be of the type shown in Ramsey Patent No. 2,108,993, although it will be understood that other types of fuse links can be employed in practicing this invention. At its upper end the fuse link 29 has a head assembly 21 which bears against the upper end of the terminal 16 to provide electrical and mechanical connection therewith. The fuse link 29 has a flexible conductor 22 extending from its other end. The flexible conductor 22 comprises a large number of small diameter wires of good conducting material such as copper. It extends downwardly through the bore of the fuse tube 17 and out at the lower discharge end where a terminal, shown generally at 23, is located. The terminal 23 includes a ferrule 24 which is arranged, as shown, to receive the lower end of the fuse tube 17. A pin 25 serves to hold the ferrule 24 in place on the lower end of the fuse tube 17.

In Figure 3 of the drawings the construction of the terminal 23 is illustrated at double the scale used in Figure 2. It will be observed that the terminal 23 includes a semi-circular tongue 26 which extends downwardly from and is integrally formed with the ferrule 24. At its lower end the tongue 26 has an integrally formed bifurcated extension 27 which has branches or arms 28 with a slot 29 therebetween through which the flexible conductor 22 can be placed as shown in Figures 2 and 3. The extension 27 is threaded as indicated at 30 for receiving a clamp nut 31. The clamp nut 31 is arranged to move a jaw 32 which is slidably mounted in the slot 29 and which has an arm 33 extending through the nut 31 from which lugs 34 project for preventing separation of the jaw 32 from the nut 31. The nut 31 and jaw 32 comprise a conventional clamp nut assembly which is em-

ployed for split bolt connectors. These clamp nuts are standard articles of commerce and ordinarily are carried in the truck of a lineman so that a supply of them always is available.

In order to fuse the cut out 10, the handle 15 is withdrawn together with the fuse tube 17 from the housing or body 14. The parts of the previously blown fuse are removed after the fuse tube 17 is unscrewed from the handle 15. The clamp nut 31 is removed. A new fuse link 20 then is inserted through the upper end of the fuse tube 17, the flexible conductor 22 being drawn through the lower discharge end of the fuse tube 17 until the head assembly 21 rests against the upper end of the terminal 16. The lower end of the flexible conductor 22 then is passed through the slot 29 and located therein as shown in Figure 3. Thereafter the clamp nut 31 is threaded onto the extension 27 with the jaw 32 in the slot 29. The clamp nut 31 is tightened so as to securely hold the flexible conductor 22 in the bottom of the slot 29. The lineman then cuts the flexible conductor 22 at 35 and discards the portion 36 of the flexible conductor 22.

It will be observed that the tongue 26 is formed so that it is offset slightly, as indicated at 37, from the outer cylindrical surface of the ferrule 24. The flexible conductor 22 can be cut as indicated at 35 close to the surface of the inwardly offset tongue 26. There is then no difficulty in inserting the fuse tube 17 which has been refused in the manner described and attached to the handle 15 into the body or housing 14 of the cut out 10. This body or housing 14 is provided with line terminals, such as the line terminals shown in Ramsey Patent No. 2,108,993, with which the terminals 16 and 23 have electrical contact. The lower terminal has an out-flared spout 38 which directs the arc products out of the fuse tube 17 and protects the lower end of the housing 14 from the heat thereof. When the terminal construction 28 is employed as described, the fuse tube 17 can be inserted in the body or housing 14 with no interference being encountered as it is moved into position through the line terminals and through the spout 38.

It will be noted that the threads 30 are removed from the front sides of the branches or arms 28 so that flat faces 39, Figures 2 and 3, are provided along which the arc root on heavy faults can move after the lower fuse link terminal has been expelled. The removal of the threads and formation of the faces 39 provide sufficient mechanical clearance so that any fusion and distortion of the branches or arms 28 due to the heat of the arc will not interfere with subsequent application of the nut 31 as described.

When the fuse link 29 is located in the fuse tube 17 as shown in Figure 2 of the drawings, the cut out 10 functions solely as an explosion fuse when the link 29 blows under overload conditions. The interrupting capacity of the cut out 10 can be improved by employing a spring and cable assembly which is indicated, generally, at 40 in Figure 4 of the drawings. This is described in more detail in Ramsey Patent No. 2,108,993. It includes a head 41 which bears against the upper end of the terminal 16. Depending from the head 41 are a coil tension spring 42 and a flexible conductor 43 which are fastened at their lower ends to a terminal 44. The terminal 44 is threaded internally for receiving the externally threaded terminal of the fuse link 29.

It is desirable in the construction shown in Fig-

ure 4 to provide for tensioning accurately the spring 42. Also it is desirable to properly locate the fuse link 20 in the fuse tube 17. For these purposes a rigid anchor contact member or cone terminal 45 is provided on the flexible conductor 22 as described in Ramsey Patent No. 2,108,993. The spring and cable assembly 40 with the fuse link 20 attached thereto is inserted through the upper terminal 16 and the fuse tube 17. The flexible conductor 22 extends out of the lower end of the fuse tube 17 and can be grasped to pull the fuse link 20 to the position shown in Figure 4 and at the same time to tension the spring 42. The flexible conductor 22 is drawn through the fuse tube 17 sufficiently far so as to permit the cone terminal 45 to be positioned in the slot 29 with the cone portion 45' thereof bearing against the outer ends of the branches or arms 28 of the extension 27. These branches or arms 28 are recessed as indicated at 46 to accommodate the cone terminal 45. After the cone terminal 45 has been positioned in the slot 29 as described so that the reaction of the spring 42 is taken up by the extension 27, the flexible conductor 22 can be cut off as indicated at 47.

In Figure 5 of the drawings the fuse link 20 is constructed as described in more detail in McMahon Patent No. 2,253,720. Specifically the flexible conductor 22 of the fuse link 20 has a cone terminal 49 which is arranged to receive and hold an indicator 50 of insulating material which, as shown in Figure 1, projects below the insulating housing 14 of the cut out 10. The indicator 50 is provided to show by its presence that the fuse link 20 has not blown and by its absence that it has blown and should be replaced. When the fuse link blows, the indicator 50 and the terminal 49 are free to drop to the ground.

It will be noted that the clamp nut 31 and jaw 32, employed as shown in Figures 2 and 3 for gripping the flexible conductor 22, are omitted when the rigid anchor contact members or cone terminals 45 or 49 are employed as shown in Figures 4 and 5 of the drawings. On the other hand the terminal 23 at the discharge end of the fuse tube 17 is constructed so that it can accommodate any of the types of fuse links which are illustrated in the drawings. It will be understood that the clamp nut 31 and jaw 32 may be employed in the construction shown in Figures 4 and 5 of the drawings where the rigid anchor contact members or cone terminals 45 or 49 are omitted, it being desired to clamp the flexible conductor 22 to the terminal 23 in the manner shown in Figures 2 and 3 and previously described.

It will be observed that the construction of the terminal 23 to accommodate either type of fuse link, i. e., with or without the rigid anchor contact member or cone terminal, is such as not to interfere appreciably with the discharge from the fuse tube 17 when the fuse link 20 blows. Furthermore, regardless of the type of fuse link that is employed, there is no obstruction provided by the terminal 23 when either type of fuse link is employed which would prevent or interfere with the insertion of the fuse tube 17 into the body or housing 14 of the cut out 10 or its withdrawal therefrom. Moreover, it can be inserted through the spout 38 even though the same has a limited opening therethrough. Since the lineman ordinarily has available a supply of these clamp nuts 31 in his truck, it is unnecessary to stock a supply of specially designed parts for use with the terminal 38 when it is desired to clamp a flexible con-

ductor 22 thereto which is not provided with a rigid anchor contact member or cone terminal.

Since certain changes can be made in the foregoing construction and different embodiments of the invention can be made without departing from the spirit and scope thereof, it is intended that all matter shown in the accompanying drawings and described hereinbefore shall be interpreted as illustrative and not in a limiting sense.

What is claimed as new is:

1. A terminal for use at the discharge end of an expulsion fuse tube and arranged to have connected thereto flexible conductors of replaceable fuse links with or without rigid anchor contact members thereon comprising, a ferrule for receiving one end of the fuse tube, a tongue extending from said ferrule away from its end which receives the fuse tube and having a longitudinal slot at its outer end, a threaded extension at the outer end of said tongue having a transverse slot therein intersecting said longitudinal slot through which a flexible conductor may be passed or against the outer end of which a rigid anchor contact member on a flexible conductor can react, a nut on said extension, and a jaw movable with said nut and slidably in said transverse slot for clamping the flexible conductor between it and the bottom of the transverse slot.

2. A terminal for use at the discharge end of an expulsion fuse tube and arranged to have connected thereto flexible conductors of replaceable fuse links with or without rigid anchor contact members thereon comprising, a ferrule for receiving one end of the fuse tube, a tongue extending from said ferrule away from its end which receives the fuse tube and having a longitudinal slot at its outer end, and a bifurcated extension at the outer end of said tongue between the prongs of which and in the longitudinal slot a flexible conductor may be passed or against the outer end of which a rigid anchor contact member on a flexible conductor can react, said extension being threaded for receiving a nut to clamp the flexible conductor to the terminal at the bottom of the opening between said prongs.

3. A terminal for use at the discharge end of an expulsion fuse tube and arranged to have connected thereto flexible conductors of replaceable fuse links with or without rigid anchor contact members thereon comprising, a ferrule for receiving one end of the fuse tube, a tongue extending from said ferrule away from its end which receives the fuse tube and having a longitudinal slot at its outer end, and a bifurcated extension constituting a prolongation of the outer end of said tongue between the prongs of which and in the longitudinal slot a flexible conductor can be passed or against the outer ends of which a rigid anchor contact member on a flexible contact member can react, said extension being threaded for receiving a nut to clamp the flexible conductor to the terminal, the front sides of said prongs being slabbed off to provide mechanical clearance between the faces thereof and a nut on said extension in the event that said faces are fused and distorted as a result of heat generated by the arc formed on blowing of the fuse link.

4. A terminal for use at the discharge end of an expulsion fuse tube and arranged to have connected thereto flexible conductors of replaceable fuse links with or without rigid anchor contact members thereon comprising, a ferrule for receiving one end of the fuse tube, a tongue ex-

7
tending from said ferrule away from its end which receives the fuse tube and having a longitudinal slot at its outer end, a threaded extension at the outer end of said tongue having a transverse slot therein intersecting said longitudinal slot through which a flexible conductor can be passed, the outer end of said threaded extension being recessed for receiving a rigid anchor member on a flexible conductor, a nut on said extension, and a jaw movable with said nut and slidable in said transverse slot for clamping the flexible conductor between it and the bottom of said transverse slot.
